ABSTRACT

A low flow safety valve according to the present invention relates to a valve construction that may be employed in conjunction with flow conduits such as well production tubing and the like. The valve construction is operative to allow the flow of production fluid through the valve structure as long as the rate of flowing pressurized fluid is above a predetermined minimum sufficient to develop a predetermined pressure differential across a restriction defined within the valve structure. As fluid flow and consequent pressure differential reduce below predetermined minimum levels, actuating means achieves closing of the valve and locking means effectively locks the valve structure against inadvertent reopening. The safety valve also includes means for unlocking and reopening the valve mechanism for the purpose of resuming production flow through the conduit structure with which the valve is associated.

LOW FLOW SAFETY VALVE

FIELD OF THE INVENTION

The present invention relates generally to safety valves and more particularly to a safety valve mechanism that is operative to allow the flow of production fluid above a predetermined volume at a given pressure and to completely shut off the flow of production fluid when such flow decreases below the predetermined allowable rate.

BACKGROUND OF THE INVENTION

In the early stages of development of the petroleum industry it was typically the practice to tap a pressurized source or reservoir of petroleum products by drilling and to allow any gas pressure that might be contained therein to dissipate to a controllable level or to a level at which the petroleum products might be recovered by pumping. The gas during this particular period was substantially unusable and was generally wasted. Where oil was blown from the well along with the escaping gas, it was the practice to collect the oil in surface ditches constructed about the well site. As the petroleum industry rapidly developed, it was discovered that the pressurized gas within production formations could be efficiently utilized to produce other petroleum products contained therein and the gas itself could be efficiently marketed in its natural state or in other physical states, such as the liquid state, for example. Various developments have been made to ensure against the loss of gas pressure within petroleum reservoirs, but most of the early developments were related to surface control valves and the like that might be manipulated manually or mechanically for flow control purposes.

Although wells may now be effectively controlled to prevent unnecessary escape of gas from the reservoir, occasionally an unforeseen circumstance will develop that may cause a well to blow wild. Surface production control equipment may be damaged by mechanical apparatus operating in the vicinity of the well site and the surface equipment of the well may be otherwise subject to various hazards of the surface environment that could result in blow-out of the well.

When the well is being produced through an offshore facility such as a production platform, the occurrence of an explosion or fire and the like is extremely hazardous to lives of personnel because of the difficulty of escape from the production facility. Offshore explosions and fires are also extremely expensive from a property damage standpoint because of the extremely expensive nature of offshore production facilities. Moreover, an oil spill that might be caused by damage to surface production flow control equipment, located on an offshore production facility, may result in pollution of an extremely large area of the shoreline thereby resulting in extensive damage to wildlife sanctuaries and the like.

Explosions, both at surface flow control equipment and within the well bore below the surface equipment, may result in sufficient damage to allow a particular well to blow wild.

Wells may also blow-out due to shifting of earth stratum through which the well bore passes and likewise, may blow-out due to insufficient structural interconnection between well cement within the well

bore and the earth stratum through which the well bore passes thereby allowing pressurized production fluid to flow around the exterior of the well casing to the surface.

When a well blows wild for any reason whatever, the expense thereof to well drilling and producing companies can be extremely great. Such expense may be caused by loss of production during the time the well is blowing wild and due to the loss of field reservoir pressure which may prevent future production of petroleum products in situ. Loss of reservoir pressure may also substantially slow the production of petroleum products or may make the production of such products extremely expensive by requiring gas lifting operations and secondary recovery operations for effective production.

It is obviously necessary to provide subsurface production flow control mechanisms that may be controllable automatically or selectively as desired to prevent well blow-outs even though surface flow control equipment may be damaged or rendered inoperative. Subsurface production flow control apparatus of this nature may be capable of preventing explosion and fires that otherwise might occur in the event of damage or malfunction of surface flow control systems. Moreover, subsurface flow control safety equipment may effectively prevent the pollution of the surface environment that might otherwise occur if an offshore well is allowed to blow wild. Since subsurface safety valve mechanisms may effectively prevent a great majority of well blow-outs and since pollution control is so extremely important from the standpoint of conservation, it is obvious that subsurface safety mechanisms are necessary to efficient functioning of the petroleum industry.

THE PRIOR ART

Various well safety systems have been developed involving both surface and subsurface safety equipment that may be actuated to a safe position either automatically as by pilot mechanisms which may be controlled by remote sensing or in the alternative may be actuated selectively or automatically, in response to the development of an adverse well condition, to stop the flow of production fluid until the production equipment may be made safe for further operation.

Offshore wells may include production equipment provided with a "safe mode" that may allow production or may shut-in the well in the event of storms or other hazardous conditions that might otherwise adversely affect production operations.

Surface and subsurface safety valve equipment has been developed that effectively achieves shut-in of surface or subsurface production flow control equipment to terminate the flow of production fluid in the event excessive well pressures should develop and in the event the flow control equipment should be subjected to excessive flow of production fluid. For the most part such safety valve equipment is velocity sensitive and remains open to allow the flow of production fluid during periods of normal or low flow of fluid but is actuated by forces developed by high velocity fluid to move the valve structure to the closed position thereby terminating the flow of production fluid.

One hazard of virtually every type of safety valve systems is that generally the valve seat and other valve closure structure is subjected at all times to adverse well conditions, such as corrosion that might be caused by the well fluid and erosion that might be caused by sand and other foreign matter flowing along with the production fluid. If the safety valve structure is eroded or corroded by flowing production fluid, it may not be capable of functioning properly in the event emergency conditions should subsequently develop.

Another adverse feature of presently available velocity sensitive safety valve mechanisms is that it is typically impossible or impractical to achieve testing of the safety mechanisms to ensure proper functioning thereof without necessitating removal of the valve structure from the well. Also, it may be necessary to remove the string of production tubing from the well which, of course, is an extremely expensive and undesirable operation.

Another problem that typically arises when velocity sensitive surface or subsurface safety valve mechanisms are employed is the likelihood that the velocity of flowing production fluid may not be sufficient to achieve effective shut-in of the well thereby allowing the well to blow under low velocity conditions. This undesirable condition, of course, is accentuated to an adverse degree if a condition of surface explosion or fire is involved. Velocity sensitive safety valves are capable of closing only after an adverse flow condition has developed, and when closure occurs, it takes the form of slamming the valve shut thereby subjecting the valve structure and other downhole well apparatus to tremendous forces that could result in serious damage. It is typically necessary to provide velocity sensitive safety valve mechanisms with control springs that are specifically designed for the particular pressure and production flow conditions to which the production equipment may be subjected. If the safety valve mechanism is allowed to remain for an extended period of time, production of the particular reservoir may reduce reservoir pressure and the consequent velocity of flowing production fluid to such a degree that the forces developed thereby may not be sufficient to achieve effective closing of the velocity sensitive safety valve even when the well is allowed to flow in unrestricted manner. Also, if reservoir pressure should increase for any particular reason substantially above the pressure and flow velocity parameters for which the velocity sensitive safety valve mechanism has been designed, the valve may permanently close thereby preventing any production of petroleum products and thereby requiring the valve to be replaced with a substitute valve that has been properly designed for the increased reservoir pressure. Velocity sensitive safety valves are obviously ineffective when undulating or rapidly changing pressure conditions are encountered. Moreover, any change in reservoir environment that may occur, for example, due to encroachment of salt water could produce adverse conditions that would interfere with proper operation of velocity sensitive safety valve mechanisms.

Accordingly, it is a primary object of the present invention to provide a novel safety valve mechanism capable of functioning properly in a down-hole well environment to shut off the flow of production fluid in the

event reservoir pressure and consequent volume of production fluid should decrease below a predetermined minimum operating level.

It is another object of the present invention to provide a novel safety valve mechanism that is effective to close the production flow passage through the well tubing upon temporary cessation of the flow of production fluid such as might be caused by closing of a surface valve.

An even further object of the present invention contemplates the provision of a novel safety valve construction that is capable of rendering surface flow control equipment safe for repair or servicing without subjecting repair or servicing personnel to hazardous conditions.

It is also an object of the present invention to provide a novel safety valve mechanism that may be simply and effectively tested to ensure proper operation thereof without necessitating expensive testing operations such as the pulling of production tubing, the provision of special testing equipment or removal of the safety valve from the tubing string.

Among the several objects of the present invention is noted the contemplation of a novel safety valve mechanism that may be reopened for further production of fluid through conduit structure with which it may be associated after having been closed under emergency conditions simply by increasing pressure within the production conduit downstream of the safety valve mechanism to a pressure in excess of pressure upstream thereof.

It is another feature of the present invention to provide a novel safety valve mechanism that may be implaced and removed by simple wire line equipment thereby providing for simple and inexpensive servicing in the event such should be indicated necessary by a testing procedure.

Still another feature of my invention includes the provision of a novel safety valve construction for a down-hole well environment that may be employed in tandem or in conjunction with velocity sensitive safety valve mechanisms to ensure complete safety control of the well regardless of the type of adverse pressure conditions that might develop either at the surface or within the reservoir being produced.

Another object of my invention involves the provision of a novel safety valve mechanism that is capable of anticipating adverse flow conditions and achieving closure without.

My invention also contemplates the provision of a novel safety valve mechanism that is of inexpensive nature and is reliable in use in addition to being low in cost.

Other and further objects, advantages and features of the present invention will become apparent to one skilled in the art upon consideration of the written specification, the attached claims and the annexed drawings. The form of the invention, which will now be described in detail, illustrates the general principles of the invention, but it is to be understood that this detailed description is not to be taken as limiting the scope of the present invention.

SUMMARY OF THE INVENTION

A preferred embodiment of the present invention may comprise an elongated generally tubular housing within which is movable disposed a sleeve member having a production passage defined therein. A valve element, which may be a spherical plug valve, if desired, is carried by the sleeve member and includes a valve passage that is communicated with the production passage in the open position of the valve to allow the flow of production fluid through the production passage. The valve housing may include means, cooperating with the valve element, to achieve movement thereof between "open" and "closed" positions, responsive to movement of the sleeve member within the housing. The sleeve member may be biased in a direction tending to achieve closure of the valve element by a compression spring or by any other suitable biasing means interposed between the sleeve member and the housing structure. A restriction means such as a choke may be disposed within the sleeve structure and is effective to achieve development of a differential pressure within the sleeve structure that creates a force of sufficient magnitude, acting upon the sleeve structure and opposing the biasing means, to overcome the biasing means and maintain the valve element in the open position as long as the flow of production fluid is above a predetermined minimum volume. In the event such flow of production fluid should decrease below the minimum operating volume, the biasing means will overcome the force of production fluid acting upon the sleeve member and induce movement of the valve element to the closed position thereof, thereby ceasing further flow of production fluid.

Detent means may be provided by the valve housing and sleeve to achieve locking of the sleeve member in the position achieving closure of the valve element thereby effectively preventing reopening of the valve element after automatic closure thereof has been achieved. Means may also be provided to unlock the detent mechanism, responsive to selective injection of pressure downstream of the valve element, to substantially balance downstream of the valve element. Such unlocking means may conveniently take the form of a pressure actuated piston having an unlocking cam thereof that disengages the detent mechanism and allows the biasing means to move the sleeve element to a position causing cooperating structure between the valve element and housing to induce movement of the valve element to the open position thereof.

BRIEF DESCRIPTION OF THE DRAWINGS

So that the manner in which the above recited features, advantages and objects of the present invention, as well as others, which will become apparent, are attained and can be understood in detail, more particular description of the invention, briefly summarized above, may be had by reference to the embodiment thereof, which is illustrated in the appended drawings, which drawings form a part of this specification.

It is to be noted, however, that the appended drawings illustrate only a typical embodiment of the invention and are, therefore, not to be considered limiting of its scope, for the invention may admit to other equally effective embodiments.

In the drawings:

FIG. 1 is a pictorial representation, illustrated partially in section, of a subsurface earth formation having a well bore extended therethrough and being lined with a well casing enclosing a production tubing containing a down-hole safety valve mechanism constructed in accordance with the present invention.

FIG. 2 is a fragmentary sectional view of the well casing structure of FIG. 1 illustrating a typical landing nipple and showing wire-line implantation and retrieval apparatus having a safety valve mechanism, constructed according to this invention, connected to the lower extremity thereof.

FIG. 3 is a sectional view of the low flow safety valve mechanism of this invention illustrating the moving parts in the normal fluid producing position thereof.

FIG. 4 is a sectional view of the safety valve structure of FIG. 3 with the internal moving parts depicted in the closed position thereof.

FIG. 5 is a fragmentary sectional view of the safety valve mechanism of FIGS. 3 and 4 illustrating the unlocking mechanism in the position thereof achieving unlocking of the latching detent mechanism.

FIG. 6 is a fragmentary sectional view of the upper portion of the safety valve mechanism of FIGS. 3 and 4, illustrating the detent unlocking mechanism in greater detail.

FIG. 7 is a fragmentary sectional view of the lower portion of the safety mechanism of FIGS. 3 and 4 illustrating the valve and choke mechanism in greater detail.

DESCRIPTION OF PREFERRED EMBODIMENT

Now referring to the drawings and first to FIG. 1, an earth formation is illustrated at 10 having a well bore 12 drilled therein which is lined with a well conduit 14 that may be cemented in place in conventional manner. Production tubing 16, typically referred to in the industry as a tubing string, extends through the well casing 14 and is sealed with respect to the well casing by a packer 18 located a convenient distance above the production zone of the earth formation. The tubular conduit 16 is open at its lower extremity to production fluid flowing through perforations in the casing 14 and conducts the production fluid upwardly through the tubing string in conventional manner.

For the purpose of shutting off the flow of production fluid through the tubing 16 in the event production flow in the tubing should decrease abnormally, it will be desirable to provide a safety valve mechanism that is responsive to predetermined decrease in the flow of production fluid to close and effectively shut off the flow of fluid. According to the present invention, such safety valve mechanism may conveniently take the form illustrated in the drawings where a safety valve mechanism is depicted generally at 20 that may be installed and removed by conventional wire-line equipment, illustrated generally at 22. It will be convenient to install the safety valve within the tubing string at a level where the temperature is high enough to prevent solidification of paraffin which might otherwise cause fouling of the movable valve parts.

With reference now to FIG. 2, the wire-line apparatus 22 is shown to include a landing nipple 24 that may be provided with externally threaded extensions 25 and 26 that receive internally threaded extremities of the production tubing 16. An annular landing

shoulder 28 may be defined within the lower extension 26 of landing nipple 24 for engagement by an annular shoulder 30 formed on a wire-line tool 32 thereby preventing the wire-line tool from descending below the level established by annular shoulder 28. Wire-line tool 32 may be provided with locking detents 34 adapted to be received within an annular locking groove 36 defined within landing nipple 24. Wire-line tool 32 may also be provided with a packing 38 of annular configuration for engagement with the cylindrical surface 40, defining a portion of the receptacle for the wire-line tool. As is typically the case, wire-line tool 32 may also be provided with a fishing neck 42 at the upper extremity thereof that may be engaged by appropriate installation and retrieval apparatus of conventional nature.

While the particular wire-line installation and retrieval apparatus 32 is illustrated in FIG. 2, it is to be understood that the particular configuration illustrated is not intended to limit the present invention. It is intended to be obvious that any suitable wire-line tool of conventional nature may be employed within the spirit and scope of the present invention. The wire-line tool 32 may be provided with a lower externally threaded extremity 44 adapted for threaded connection to internal threads 46 formed within the upper extremity of an upper housing section 48 of the safety valve mechanism 20, thereby effectively supporting the safety valve in depending relation from the wire-line tool 32.

The safety valve mechanism 20 may include a housing structure defined by upper housing section 48, latching section 50, spring housing section 52, valve section 54 and a terminal cap section 56. Latching section 50 may be provided with externally threaded portions 58 and 60 for threaded engagement with the internally threaded portion 62 of upper housing section 48 and the internally threaded portion 64 of the spring housing section 52. Spring housing section 52 may be provided with an externally threaded extension 66 at the lower extremity thereof to which may be threaded externally engaged the internally threaded portion 68 of the valve section 54. Terminal cap section 56 may be provided with an externally threaded extension 70 that may be threaded received by internal threads 72 defined within the lower extremity of valve section 54.

The valve mechanism 20 may be provided with an internal sleeve 74, the lower extremity of which is shown in detail in FIG. 7, which may be provided with a reduced diameter portion 76 defining an annular shoulder 78 adapted for engagement by a compression spring member 80 that is disposed within spring housing section 52 and interposed between shoulder 78 and an upper annular shoulder 82 defined by the lower extremity of latching section 50. Compression spring 80 is operative to bias the sleeve member 74 downwardly, as illustrated in the drawings. Although compression spring 80 is illustrated as a metal helical spring, it is intended that any appropriate biasing means may be incorporated into the valve structure to achieve biasing of the sleeve member 74 downwardly in a direction opposing the flow of production fluid without departing from the spirit and scope of the present invention. It is to be understood that the mechanism for imparting movement of the valve element to the closed position thereof may take any desirable form other than a bias-

ing means. For example, a servo mechanism may achieve closure of the valve element responsive to sensing the predetermined flow condition necessary for closure of the safety valve. A production passage 84 may be defined within the sleeve 74 and serves to conduct the flow of production fluid through the valve structure.

The lower extremity of sleeve 74 may be provided with external threads 86, as illustrated in FIG. 7, to which may be threadedly connected the internally threaded portion 88 of a valve and choke support element 90. The lower extremity of sleeve 74 may also be provided with an enlarged diameter choke recess defined by a generally cylindrical bore 92 within which is received a choke member 94 having a restricted flow passage 96 formed therethrough. Annular shoulders 98 and 100 defined, respectively, within sleeve 74 and the valve and choke support element 90, cooperate to retain the choke member 94 in substantially fixed relation relative to the sleeve structure. Annular sealing means 102 may be provided to establish sealed relation between cylindrical surface 92 and sleeve member 74 which, according to the present invention, if desired, may take the form of an O-ring, as illustrated, or, in the alternative, the sealing element 102 may take any other appropriate conventional configuration within the spirit and scope of the present invention.

The valve and choke support element 90 may be provided with an annular groove 104 within which is retained valve support elements, illustrated in broken line at 106, having support extensions 108 defined thereon to which may be connected the trunnions 110 of a rotatable spherical plug member 112. The plug member or valve element may be provided with an internal valve passage 114 that is adapted, in the open position of the valve element, to communicate with a flow passage 116 defined within the support element 90. Support element 90 may also be provided with an annular seat surface 118 disposed for engagement with a spherical working surface 120 on the plug or valve element 112. It is intended that the valve element 112 may take any other appropriate form other than the spherical form within the spirit and scope of this invention.

For the purpose of imparting rotatable movement to valve element 112 between the "open" and "closed" positions thereof, a cam groove may be formed in the valve element, as illustrated in broken line at 122, within which may be received a cam element 124 in the form of a pin carried in fixed relation by the valve section 54 of the valve housing. As the valve element is moved downwardly by the sleeve 74 and valve and choke support element 90 in the direction opposing the flow of production fluid, the interengaged relation between cam element 124 and the cam groove 122 will be operative to effect 90° rotation of valve element 112 from the "open" position thereof, as illustrated in FIGS. 3 and 7, to the "closed" position thereof, as illustrated in FIG. 4.

Since the flow of production fluid through the valve passage 114 may be quite high, it may be appropriate to provide a means for stabilizing the valve element against shattering forces or vibration that might be created by fluid turbulence and also a means may be provided to direct the flow of fluid smoothly through

the valve passage 114. According to the present invention, such stabilizing means may conveniently take the form illustrated in detail in FIG. 7 where a valve stabilizer 126 is shown to be movably disposed within the valve section portion 54 of the valve housing and is provided with a seat surface 128 disposed for engagement with the spherical working surface 120 of valve element 112. A biasing means 130 which, if desired, may take the form of a metallic helical compression spring, may be interposed between a shoulder 132 defined on the valve stabilizer 126 and an annular shoulder 134 defined by the upper extremity of terminal cap section 56 of the valve housing structure. The compression spring 130 is operative to bias the valve stabilizer 126 into engagement with the valve element 112, thereby serving to firmly encapsulate the valve element between sealing surfaces 128 and 118 to enhance the sealing ability of the valve element and to prevent vibration of the valve element by fluid turbulence. The valve stabilizer 126 may also be provided with an extension 136 defining an external guide surface 138 that serves to maintain positive alignment of the valve stabilizer in any particular position thereof and to allow movement of the valve stabilizer as the valve element is reciprocated during opening and closing movements thereof.

A wiping ring 140 may be received within an annular groove 142 formed in the terminal cap section 56 and may be disposed for close fitting relation with the cylindrical surface 138 of the valve stabilizer 126 to prevent foreign matter, that might be contained within the flowing production fluid, from entering the annulus defined between the valve housing and the internal movable parts of the safety valve. The wiper element 140 is not provided for the purpose of establishing a fluid-tight seal, because it is desirable, as will be explained in detail hereinbelow, that fluid pressure be communicated into the annulus for valve control purposes. Fluid communication, from the terminal cap portion 56 of the valve housing to the valve element, may be conveniently provided by fluid passage 144 defined within valve stabilizer 126 that may be appropriately disposed coextensive with valve passage 114 in the open position of the valve element.

With reference now particularly to FIG. 6, a means may be provided for the purpose of locking the sleeve element 74 in the downward position thereof subsequent to actuation of valve element 112 to its closed position and, according to the present invention, such means may conveniently take the form illustrated in FIG. 6 where the sleeve 74 is shown to be provided with an annular locking groove 146 defining an annular shoulder 148. The latching section 50 of the housing structure may include a plurality of latching fingers 150, each being provided with latching detents 152 capable of being received within the latching groove 146 upon movement of sleeve element 74 to the lowermost position thereof. Latching fingers 150 may be spring biased toward such latching engagement to cause locking shoulders 154 of the detents 152 to engage the annular shoulder 148 to restrain or lock the sleeve member 74 in the downward position thereof. It is also within the scope of this invention to provide means other than a mechanical mechanism for maintaining the valve element in its closed position until it

desired to open the valve. A servo mechanism or any other appropriate system may be employed to open the valve selectively or automatically upon restoration of the "safe operating condition."

- 5 After the sleeve 74 has moved downwardly to close the valve element 112 and the detents 152 have moved into locking engagement within the latching groove 146, subsequent pressure change upstream of valve element 112 will not be effective to achieve reopening of the valve element. After automatic emergency locking of the sleeve 74 in the valve closing position thereof, it will subsequently become appropriate to unlock the sleeve when it is desired to achieve movement of the valve element to the open position thereof to resume the flow of production fluid. An unlocking means is provided, which, according to the present invention, may conveniently take the form illustrated in FIG. 6 wherein an annular unlocking piston 156 may be movably disposed within an annular chamber 158 defined between an inner wall 160 of upper housing section 48 and an external cylindrical surface 162 defining the upper extremity of sleeve 74 above locking groove 146. Unlocking piston 156 may be provided with an internal sealing element 164 and an external sealing 166 to maintain sealing relation between the unlocking piston and the cylindrical surfaces 162 and 160, respectively.

For the purpose of releasing the latched connection 30 between detent members 152 and the annular shoulder 148, defined by latching groove 146, an unlatching extension 168 may be formed integrally with unlocking piston 156 and may be provided with a cam surface 170 disposed for engagement with opposed cam surfaces 35 172, defined at the upper extremity at each of the latching fingers 150. As unlocking piston 156 is moved downwardly, cam surface 170 will move into engagement with cam surfaces 172 and will actuate the spring fingers outwardly, thereby causing disengagement of the locking shoulders 154 of the spring fingers from the annular shoulder 148 defined on the sleeve 74. After this unlocking movement has occurred, the sleeve 74 will have been released and will be capable of being moved upwardly to impart rotation to valve element 112 to the open position thereof to resume the flow of production fluid through the valve structure.

Unlocking piston 156 may be designed for movement by fluid pressure that may be applied either by the 50 production fluid or by an actuating fluid applied under pressure from a source located downstream of the safety valve structure. While the valve 112 is disposed in the "production mode" thereof as illustrated in FIG. 7, production fluid under pressure will maintain the unlocking piston 156 at the upper limit of its travel where further upward movement thereof is prevented by a stop shoulder 174.

OPERATION

60 Assuming the safety valve mechanism of the present invention to be disposed in the open position thereof, as illustrated in FIGS. 3, 6 and 7, it will be apparent that production fluid will flow from the well casing into the open lower extremity of the safety valve mechanism 20 under reservoir pressure. Since valve element 112 will be maintained in its open position in the "production mode," fluid pressure will be communicated through

the valve passage 114, the flow passage 116 and through the restricted passage 96 of choke 94 into production flow passage 84.

As the pressurized production fluid passes through the restricted orifice defined by choke passage 96, a pressure differential will be created across the choke thereby producing a force acting upon the sleeve 74 in a direction opposing the bias of compression spring 80. The force acting through sleeve 74 will be sufficient during normal production flow to overcome the bias of compression spring 80 and maintain the sleeve member 74 at the uppermost position thereof where an annular shoulder 176 of the valve and choke support element 90 is disposed in restraining engagement with a stop surface 178 defined by the lower extremity of spring housing section 52 of the valve housing.

The annulus between the valve housing wall and the internal movable parts of the safety valve structure will be subjected to reservoir pressure passing the wiping ring 140 which acts upon the lower surface area defined by the annular unlocking piston 156. Since a reduced pressure will be acting upon the surface area defined by the upper extremity of the unlocking piston 156 by virtue of the choke reduction, the fluid pressures acting upon the piston 156 will be unbalanced thereby creating a resultant force biasing the piston upwardly into engagement with the stop surface 174. The valve and choke support element 90, along with valve element 112, will be moved to their uppermost positions by sleeve 74 and the valve stabilizer 126 will be biased by spring 130 to its uppermost position maintaining a stabilizing bias upon the spherical valve element 112.

In the event the flow of production fluid should decrease for any reason whatever, such as by reduction in reservoir pressure, by temporary closing of surface production control valves or by the creation within the production tubing of a pressure approaching the reservoir pressure, the resultant force acting upon sleeve 74, created by the pressure differential across choke 94, will be insufficient to overcome the bias of compression spring 80. The compression spring then will urge the sleeve element 74 downwardly thereby moving the valve and choke support element 90 and consequently the spherical plug valve element 112 downwardly and causing the cam pin 124 acting through cam groove 122 to actuate the valve element to the closed position thereof, as illustrated in FIG. 4. Downward movement of the sleeve and valve assembly is limited under this condition by an annular stop shoulder 178 defined on the valve stabilizer 126 that is adapted for engagement with shoulder surface 134.

If in the valve closed position of the safety valve, as shown in FIG. 3, the casing below the safety valve should remain under reservoir pressure even under a reduced pressure condition, such fluid pressure will act through the annulus defined between the valve housing wall structure and the internal moving parts of the valve structure and will bear upon the lower surface area defined by the annular unlocking piston 156, thereby maintaining the unlocking piston at the uppermost position thereof, as illustrated in FIG. 6.

If the production pressure conditions should resume a normal level, subsequent to closing of the spherical plug 112, the valve construction will remain in a closed

position because of the latching engagement between the detents 152 of spring fingers 150 which will maintain engagement with the annular shoulder 148 of sleeve 74, thereby presenting the sleeve member from again moving upwardly which would obviously allow opening of the valve element.

The safety valve construction may be opened by selective application of actuating fluid pressure above the valve 112 at a pressure level in excess of reservoir pressure. Such actuating fluid pressure is effective to develop a resultant force, acting upon the upper surface area defined by annular unlocking piston 156, that is greater than the force created by reservoir pressure acting upon the lower surface area of piston 156. The piston therefore will be induced to move downwardly causing the cam surface 170 of the unlocking extension 168 to engage cam surfaces 172 of the spring fingers 150 thereby urging the spring fingers outwardly and releasing shoulders 154 of locking detents 152 from the annular shoulder 148 of the sleeve element. After the spring fingers have been unlatched from the sleeve element there will exist a substantially balanced pressure condition within the valve structure due to substantial balancing between reservoir pressure and the actuating pressure injected into the tubing above the valve element to cause the unlocking movement. Compression spring 80, under this condition, will continue to maintain the sleeve element biased downwardly, thereby maintaining the spherical plug 112 in a closed position thereof.

It will then be necessary to reduce fluid pressure above the valve element simply by bleeding off the same by appropriate manipulation of surface flow control valves, thereby causing reservoir pressure to overbalance actuation pressure above the safety valve. When sufficient pressure differential occurs across the choke to produce a force, acting on the sleeve, that is sufficient to overcome the bias of compression spring 80, the plug member, the valve and choke support element 90 and the sleeve element 74 will be forced upwardly and will thereby cause the plug member 112 to be rotated to the open position thereof by virtue of the interengagement between cam pin 124 and plug groove 122. This movement can take place slowly thereby preventing any slamming of the valve parts which might otherwise cause damage to the valve. During the opening movement the unlocking extension 168 maintains its engagement with spring fingers 150 until sufficient resultant force is developed to cause the unlocking extension to cam the spring fingers outwardly to achieve releasing thereof. This feature eliminates the possibility of relocking of the sleeve which might otherwise occur if the piston were free to move upwardly upon application of insignificant pressure differential. After plug member 112 has been fully opened and full production flow has been resumed, the valve construction will remain static until such time as the flow of pressurized fluid is again reduced to the predetermined minimum level necessary for automatic actuation of the valve to its closed position.

Assuming that the reservoir pressure remains at an optimum level, but it is deemed appropriate to conduct a test to determine whether the valve construction is operative, it will simply be necessary to manipulate surface flow control equipment to reduce the flow of

production fluid through the safety valve below the predetermined minimum volume required for automatic actuation of the safety valve. If the valve construction is operative, the compression spring 80 will bias sleeve element 74 downwardly inducing closing of the plug member 112 in the manner discussed hereinabove. Subsequent to the completion of a successful test the safety valve may again be reopened to resume the flow of production fluid by injection of fluid pressure into the tubing above the safety valve in the manner discussed hereinabove. The testing procedure is simple, reliable and quite inexpensive. It becomes necessary to remove the safety valve from the well for repair or replacement only when it is determined, through the testing procedure indicated above, that the valve construction is in need of repair or replacement. Moreover, replacement or repair procedures are readily and inexpensively accomplished because it is unnecessary to remove the tubing string from the well. The wire-line tool 32 may be unlocked and retrieved in conventional manner along with the safety valve attached thereto, and subsequent to the valve repair or replacement procedure, may be reinstalled within the well in simple conventional manner.

It will be evident from the foregoing that I have provided a novel safety valve mechanism that is capable of functioning properly in a down-hole well environment to shut off the flow of production fluid in the event that flow of production fluid should decrease for any reason whatever below a predetermined operative level. The safety valve mechanism of my invention also effectively achieves closing of the production flow passage through the well tubing upon temporary cessation of the flow of production fluid such as might be caused by closing of a surface valve or by creation within the production tubing of a back pressure sufficient to at least temporarily reduce the flow of production fluid below the predetermined minimum operating level. I have also achieved the provision of a novel safety valve mechanism that may be simply and effectively tested to ensure proper operation thereof at all times without necessitating an expensive testing operation and without requiring removal of the production tubing from the well. Also with the flow of production fluid shut down by simple valve closure the flow of production fluid may be restrained solely by the safety valve mechanism while the surface flow control mechanism may be serviced or repaired without subjecting personnel to hazardous conditions.

After an emergency shut down, a testing procedure or a procedure involving repair of surface flow control equipment, the safety valve mechanism of my invention may be reopened simply by applying fluid pressure within the production tubing above the safety valve in the manner discussed hereinabove. Such reopening can be achieved effectively without involving slamming of the valve parts which might otherwise occur upon sudden subjection of the valve structure to reservoir pressure. The safety valve mechanism of my invention is adapted for simple connection to a conventional wire line tool thereby allowing the safety valve to be in place and retrieved by conventional wire line production tool apparatus. This feature effectively eliminates any necessity for removing the tubing string if it is determined that the safety valve should be cleaned, repaired

or replaced. Moreover, the safety valve mechanism of my invention can be effectively employed in a down hole well environment in tandem or in conjunction with a conventional velocity sensitive safety valve mechanism, if desired, thereby lending safety valve capability under virtually all possible pressure and flow conditions that might develop either at the surface or within the reservoir being produced. It is therefore seen that this invention is one well adapted to attain all of the objects and advantages hereinabove set forth together with other advantages which will become obvious and inherent from a description of the apparatus itself. It will be understood that certain combinations and subcombinations are of utility and may be employed without reference to other features and subcombinations. This is contemplated by and is within the scope of the present invention.

As many possible embodiments may be made of this invention without departing from the spirit or scope thereof, it is to be understood that all matters hereinabove set forth or shown in the accompanying drawings are to be interpreted as illustrative and not any limiting sense.

25 What is claimed is:

1. A safety valve assembly comprising:
housing means;
valve means disposed within said housing means and being movable between open and closed positions to control the flow of production fluid through said valve assembly;
means urging said valve means toward the closed position thereof;
means responsive to predetermined rate of flow of production fluid through said valve assembly for maintaining said valve means in the open position thereof;
means closing said valve means upon decrease in the flow of production fluid below said predetermined rate of flow;
means locking said valve means against reopening after closure thereof by said urging means; and
means releasing said valve means from the locked condition thereof in response to application of predetermined fluid pressure downstream of said valve means.

2. A safety valve assembly as recited in claim 1:
valve sleeve means movably disposed within said housing means and defining a flow passage through said safety valve assembly;
said valve means being movably supported by said sleeve means and having a flow port for registry with said flow passage in the open position of said valve means;
said means biasing said valve means toward the closed position thereof being resilient means interposed between said housing and said sleeve means;
said means for maintaining said valve in the open position thereof comprising flow passage means formed in said sleeve means for conducting the flow of production fluid therethrough; and
means restricting said flow passage and causing fluid flowing through said flow passage to develop a pressure differential within said flow passage across said restricting means and thereby develop a resultant force acting on said sleeve means and

opposing said biasing means, said resultant force being effective to overcome said biasing means and maintain said sleeve means at a position causing said valve means to be maintained in the open position thereof in response to a predetermined rate of flow through said flow passage.

3. A safety valve assembly as recited in claim 1: sleeve means being disposed for reciprocation within said housing means and having flow passage means defined therethrough; and said valve means being a spherical plug valve rotatably carried by said sleeve means and having a flow port formed therein for registry with said flow passage of said sleeve means, said valve means being rotatable between open and closed positions thereof responsive to reciprocation of said sleeve means.

4. A safety valve assembly as recited in claim 1: sleeve means disposed for reciprocal movement within said housing means having a production flow passage defined therein;

said valve means being movably carried by said sleeve means and being movable between open and closed positions thereof responsive to reciprocal movement of said sleeve means to control the flow of production fluid through said production flow passage;

said means locking said valve means comprising latch means carried by said housing; latch detent means defined in said sleeve; and said latch means and detent means interengaging to lock said sleeve against movement upon movement of said sleeve to a position causing closure of said valve means by said biasing means in response to predetermined decrease in differential pressure within said valve assembly.

5. A safety valve assembly comprising: elongated tubular housing means being open at each extremity thereof;

sleeve means being movably disposed within said housing and having a production passage formed therein;

means urging said sleeve means toward one extremity of said housing;

valve means being carried by said sleeve means and being movable between open and closed positions thereof to control the flow of production fluid through said production passage;

said urging means urging said valve means toward said closed position;

means responsive to predetermined flow of production fluid through said production passage for urging said sleeve means against the bias of said valve means in the open position thereof;

said urging means closing said valve means upon reduction of the flow of production fluid below said predetermined flow;

means locking said sleeve means against movement upon closure of said valve means; and means releasing said sleeve from the locked condition thereof in response to application of predetermined fluid pressure downstream of said valve means.

6. A safety valve as recited in claim 5: means defining a restriction within said production passage; and the flow of pressurized production fluid through said restriction developing a pressure differential across said restriction and developing a resultant force acting on said sleeve means and opposing the force of said urging means.

7. A safety valve as recited in claim 5: said means for urging said sleeve means against the force of said urging means defining a restriction within said production passage; the flow of a predetermined volume of pressurized production fluid through said restriction developing a pressure differential across said restriction and developing a resultant force overcoming said urging means and maintaining said valve means in the open position thereof;

said means locking said valve element in the closed position thereof upon closure of said valve element including latch means carried by said housing; latch detent means being defined in said sleeve means; and

said latch means and detent means interengaging to lock said sleeve against movement upon movement of said sleeve to a position causing closure of said valve means by said biasing means in response to predetermined decrease in differential pressure within said valve assembly.

8. A safety valve as recited in claim 7: means for selectively unlocking said valve element and allowing opening thereof.

9. A safety valve as recited in claim 5: said means locking said valve element comprising a latching groove defined in said sleeve means; a plurality of spring fingers carried by said housing and having detent means defined thereon for locking engagement within said latching groove upon movement of said sleeve to a position closing said valve means; and means for selectively disengaging said spring fingers from said latching groove.

10. A safety valve as recited in claim 9: said means for selectively disengaging said spring fingers comprising piston means having unlatching cam means disposed thereon; and said piston being movable to the unlatching position thereof responsive to application of fluid pressure downstream of said valve and being movable to a retracted position by pressure of said production fluid.
